(57) **CLAIM**

The ornamental design for an automotive switch electrical connector with latching feature, as shown and described herein.

DESCRIPTION

FIG. 1 is a front, top and right side perspective view of an automotive switch electrical connector with latching feature showing our new design;

FIG. 2 is a back, bottom and left side perspective view thereof;

FIG. 3 is a left side elevational view thereof;

FIG. 4 is a right side elevational view thereof;

FIG. 5 is a front elevational view thereof;

FIG. 6 is a back elevational view thereof;

FIG. 7 is a top plan view thereof;

FIG. 8 is a bottom plan view thereof; and,

FIG. 9 is a back, bottom and left side perspective view thereof, in use condition.

The broken lines in the drawing views are included for the purpose of illustrating portions of the automotive switch electrical connector with latching feature that form no part of the claimed design.
